UNITED STATES PATENT OFFICE.

JACOB H. CASSIDY, OF LEAVENWORTH, KANSAS.

TONGUE-SUPPORT.

SPECIFICATION forming part of Letters Patent No. 458,690, dated September 1, 1891.

Application filed May 12, 1891. Serial No. 392,492. (No model.)

To all whom it may concern:

Be it known that I, JACOB H. CASSIDY, a citizen of the United States, residing at Leavenworth, in the county of Leavenworth, State 5 of Kansas, have invented certain new and useful Improvements in Tongue-Supports for Vehicles, of which the following is a full, clear, and exact description, reference being had to the accompanying drawings, forming 10 a part hereof.

My invention relates to an improvement in tongue-supports for vehicles; and it consists of the novel construction hereinafter fully set forth and described.

15 This invention is designed to be used with the coil-spring tongue-supports illustrated in the accompanying drawings; and its objects are, first, to provide an adjustment for said coil-spring tongue-support which will be 20 positive and efficient and which may be adjusted at will or whenever the supporter may become worn without having to employ a blacksmith and without bending the shanks of the spring; second, to accomplish this by 25 introducing an adjustment plate or wedge between the ends of the spring and the lower surface of the tongue; third, to attain these ends with simplicity and economy, which I do by constructing and utilizing the devicee 30 illustrated in the accompanying drawings, in which—

Figure I is a perspective view of the front part of the running-gear of a vehicle elevated to an angle sufficient to show the manner in which my invention is applied; and 35 Fig. II is a detail in perspective of the adjustment-plate, showing slots and bolts by which it is adjusted.

Referring to the drawings by letter, A represents the front portion of the running-gear 40 of a wagon mounted on wheels B B and provided with a tongue a.

C C are the coil-springs, suitably strung on the tongue-rod, their shanks secured in position on the bottom of the axle, and, if found desirable, are held there by loops c c or their equivalent.

c' c' are the front extensions of said coil-spring supports, which bear against the under side of the adjustment-plate D, which in turn is secured to the lower surface of the tongue by suitable bolts D' and D². The shank of said adjustment-plate is provided

with an elongated adjustment-slot d, through which the adjusting bolt-screw D² passes. 55 The end of this shank is provided with a perforation d', through which passes the keeper-bolt D', which is for the purpose of holding the adjustment-plate rigidly in position. 60

D³ are the extensions or wings of the adjustment-plate, provided at their outward extremities with downwardly-extending lugs d² d², which form receptacles and rests for the front ends or shanks of the supports here- 65 tofore referred to.

Heretofore the only way in which the supporter could be adjusted was to detach it from the vehicle and subject the shanks to a heating process, and then bend same to the required form. This frequently resulted in taking the temper from the coils and leaving them almost worthless. Now by using my adjustment-plate the supporter may be adjusted at will by slackening up on the slot-bolt D² and removing the keeper-bolt D', then sliding the adjustment-plate forward or back, as desired, and again seating the keeper-bolt and tightening the slot-bolt. 75

Having thus fully described my invention, 80 what I claim as being new, and desire to secure by Letters Patent, is—

1. In combination with a coil-spring C, the adjustable plate for a tongue-support, constructed with the perforation d' and an elongated adjustable slot d, the extending wings D³, with lugs d², and the keeper and adjusting bolts D' and D², operating in the perforation d' and slot d, as set forth and described. 85

2. In combination with the front gear of a vehicle, a tongue-support consisting of a plate D, having in its end a perforation d' and a slot d, wings D³, and downwardly-extending lugs d², bolts D' and D², passing through said perforation and slot, and coiled springs C, 95 coiled around the tongue-rod and having their rear ends secured to the lower face of the axle and their front ends resting up against the lower face of the wings D³, substantially as shown and described. 100

In testimony whereof I affix my signature in presence of two witnesses.

JACOB H. CASSIDY.
